US00D583771S

(12) **United States Design Patent**
Lubanski

(10) **Patent No.:** **US D583,771 S**
(45) **Date of Patent:** **** Dec. 30, 2008**

(54) **MALE CABLE PROTECTOR CONNECTOR**

(75) Inventor: **Thomas M. Lubanski**, Claremont, CA
(US)

(73) Assignee: **Peterson Systems International, Inc.**,
Duarte, CA (US)

(**) Term: **14 Years**

(21) Appl. No.: **29/250,620**

(22) Filed: **Nov. 22, 2006**

(51) LOC (8) Cl. **13-03**

(52) U.S. Cl. **D13/155**

(57) **CLAIM**

The ornamental design for a male cable protector connector, as shown and described.

DESCRIPTION

FIG. 1 is a perspective view of a male cable protector connector according to the present invention;

FIG. 2 is a close up perspective view of the male cable protector connector according to the present invention;

FIG. 3 is a top view of the male cable protector connector according to the present invention; and,

FIG. 4 is a side elevation view of the male cable protector connector according to the present invention.

The broken lines in the figures are included for the purpose of illustrating environmental structure and form no part of the claimed design.
